UNITED STATES PATENT OFFICE.

ROYCE M. STRICKLAND, OF NEW HAVEN, CONNECTICUT, ASSIGNOR TO THE GEOMETRIC TOOL CO., OF NEW HAVEN, CONNECTICUT, A CORPORATION.

SELF-OPENING DIE HEAD.

Application filed July 29, 1926. Serial No. 125,664.

Fig. 1 is a view in side elevation of a die-head embodying my invention;

Fig. 2 is a view thereof in front elevation;

5 Fig. 3 is a transverse sectional view on the line 3—3 of Fig. 1;

Fig. 4 is a view of the die-head in central longitudinal section on the line 4—4 of Fig. 2, the parts being shown in the positions due 10 them when the chasers are closed, preparatory to a threading operation;

Fig. 5 is a corresponding view, but showing the parts in the positions due them at the conclusion of the threading operation 15 and at the instant of the conclusion of the tripping operation and before the die-head has tripped, which, however, will instantly follow;

Fig. 6 is a corresponding view, but showing the parts in the positions due them at the conclusion of the chaser-retracting movement of the parts;

Fig. 7 is a view of the die-head in rear end elevation; and

25 Fig. 8 is a broken sectional view on the line 8—8 of Fig. 2.

My invention relates to an improvement in self-opening die-heads, the object being to produce a simple, effective and durable 30 die-head constructed with particular reference to its provision with sensitive and responsive tripping-means.

With these ends in view, my invention consists in a self-opening die-head having certain 35 details of construction as will be hereinafter described and pointed out in the claims.

In carrying out my invention, as herein shown, I employ a skeletonized die-head 40 body 10 provided with a rearwardly-extending shank or spindle 11 and formed in its forward face with four equidistant radial grooves 12 for the reception of a like number of radially-movable chasers 13—13. Each 45 chaser is provided with a rearwardly-extending pin 14 engaged by a spring-plunger 15 normally tending to move the chaser radially outward, so that, under normal operating conditions, the beveled outer 50 end 16 of each chaser is forced into engagement with a correspondingly inclined bevel 17 formed upon the inner face of the outer end of a chaser-operating sleeve 18 having rectilinear movement upon the die-head body 55 10 and upon which it bears at its forward

end, while its rear end bears upon an adjustable abutment-member 19 threaded upon the die-head body 10.

For releasably holding the operating-sleeve 18 forward in its chaser-closing position, as shown in Fig. 4, I employ a plate-like locking-member 20 having diametrical movement with respect to the die-head and formed with a central aperture 21 for the reception of the adjustable abutment-member 19, which it embraces. The said locking-member is located in a groove 22 formed upon the interior periphery of the rear end of the operating-sleeve 18. One side of this groove is intersected by a radial passage 23 leading to the exterior periphery of the said operating-sleeve, so that the locking-member may be inserted radially thereinto. The locking-member 20 is formed with an outwardly-extending finger 24, beveled at its outer end and adapted to be engaged by a cam-surface 25 formed upon the interior periphery of a tripping-sleeve 26, which is also provided with a peripheral groove 27 and has limited rectilinear movement upon the operating-sleeve 18, which latter is reduced in diameter, as at 28, for its accommodation.

At a point directly opposite the finger 24 and adjacent the aperture, the locking-member 20 is adapted to engage, under the urge of a flat spring 29, with a portion of a forwardly-facing annular abutment-shoulder 30 formed upon the abutment-member 19.

Normally tending to move the operating-sleeve rearward with respect to the body 10, to permit the retraction of the chasers 13 under the urge of their spring-plungers 15, are helical springs 31 (Figs. 2 and 8) housed within rearwardly-opening recesses 32 in the said body and engaging a forwardly-facing shoulder 33 of the chaser-operating member. To releasably check the rearward movement of the operating-sleeve 18 under the urge of the springs 31 just described, when the said sleeve reaches its intermediate or chaser-retracted position, as shown in Fig. 6, I employ a pivotal stop-lever 34, swinging upon a pin 35 within a recess 36 formed in the abutment-member 19 and normally held in its outwardly-swung position by a spring-pressed plunger 37 (Fig. 7).

As shown in Figs. 1 to 4 inclusive, my improved die-head is in its closed position, ready for a threading operation, at which

time the locking-member 20 is yieldingly held in engagement with the abutment-shoulder 30 of the abutment-member 19, whereby the chaser-operating sleeve 18 is 5 locked in its forward position against the counter-urge of the springs 31. At this time, also, the tripping-sleeve 26 is at the limit of its forward movement.

At a predetermined point in the threading operation, during which the die-head is moved toward the work while rotating, the concurrent movement of the tripping-sleeve 26 is arrested by any suitable abutment set in the machine in which the die-head is being used, in the usual and well-known manner, according to the character of the work. When the tripping-sleeve is thus arrested, the continued forward movement of the remaining parts of the die-head causes the 20 finger 24 of the locking-member 20 to ride down the cam-surface 25 of the tripping-sleeve and eventually disengage the portion of the locking-member lying opposite the finger 24 from the abutment-shoulder 30 of 25 the abutment-member 19, as shown in Fig. 5 of the drawings. The springs 31 now assert themselves to move the operating-sleeve 18 rearward with respect to the body 10, until its movement is checked by its engagement with the stop-lever 34, so as to permit 30 the chasers 13 to be moved radially outward, away from the work, by their spring-actuated plungers 15, as shown in Fig. 6.

In the event that it is desired to remove 35 the chasers 13 from the die-head for any reason, the stop-lever 34 may be pressed inward to permit the sleeve 18 to slide rearwardly over it to an extent sufficient to entirely disengage the forward end of the said 40 sleeve from the chasers.

I claim:

1. A self-opening die-head, having a body; chasers mounted therein; a reciprocating operating-sleeve for moving the said 45 chasers; a plate-like locking-member extending transversely of the die-head and formed with a segmental locking-surface and having movement transverse to the axis of the die-head for holding the said operating-sleeve in its chaser-closing position; a tripping-sleeve mounted upon the said operating-sleeve and having rectilinear movement with respect to the said body and operating-sleeve in a path substantially at a 50 right angle to the path of movement of the said locking-member and adapted to move said locking-member into its unlocking position.

2. A self-opening die-head, having a 55 body; chasers mounted therein; a reciprocating operating-sleeve for moving the said

chasers; an abutment-member on the said body; an apertured locking-member co-acting with and embracing the said abutment-member and having movement transverse to the axis of the die-head for holding the said operating-sleeve in its chaser-closing position; a tripping-sleeve mounted upon the said operating-sleeve and having rectilinear movement with respect to the said body and operating-sleeve in a path substantially at a 60 right angle to the path of movement of the said locking-member and adapted to move said locking-member into its unlocking position.

3. A self-opening die-head, having a body; chasers mounted therein; a reciprocating operating-sleeve for moving the said chasers having its rear end shouldered and reduced in external diameter; an adjustable abutment-member on said body; an apertured locking-member co-acting with and embracing the said abutment-member and having movement transverse to the axis of the die-head for holding the said operating-sleeve in its chaser-closing position; a tripping-sleeve having its rear end shouldered and reduced in internal diameter for engagement with the reduced portion of the operating-sleeve, upon which it has relative rectilinear movement in a path substantially at a right angle to the path of movement of the said locking-member, which latter it is adapted to move into its unlocking position.

4. A self-opening die-head, having a body; chasers mounted therein; a reciprocating operating-sleeve for moving the said chasers having its rear end shouldered and reduced in external diameter and its interior periphery formed with a groove and with a wide radial passage connecting the said groove to the exterior periphery; an adjustable abutment-member on said body; an apertured locking-member located within the above mentioned groove and co-acting with and embracing the said abutment-member and having movement transverse to the axis of the die-head for holding the said operating-sleeve in its chaser-closing position; a tripping-sleeve having its rear end shouldered and reduced in internal diameter for engagement with the reduced portion of the operating-sleeve, upon which it has relative rectilinear movement in a path substantially at a right angle to the path of movement of the said locking-member, which latter it is adapted to move into its unlocking position.

In testimony whereof, I have signed this specification.

ROYCE M. STRICKLAND.
